PENCIL

John T. Hendrick, Cofer, Ky.

Application June 13, 1941, Serial No. 397,978

2 Claims. (Cl. 120—9)

This invention relates to pencils and has for an object to provide a pencil having a barrel forming a grip adapted to house a short conventional pencil to prevent the lead becoming broken off when the pencil is not in use.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation of a pencil constructed in accordance with the invention.

Figure 2 is a longitudinal sectional view of the pencil shown in Figure 1 with the short pencil projected from the barrel to operative position.

Figure 3 is a longitudinal sectional view of the pencil with the short pencil retracted within the barrel.

Referring now to the drawing in which like characters of reference designate similar parts in the various views, 10 designates a cylindrical cap adapted to receive a short pencil 11, the cap being provided with a frustum shaped upper end 12 and also being provided with an outer annular shoulder 13 at the bottom of the frustum shaped upper end.

A barrel 14 forms a grip and is provided near its lower end with an inner annular shoulder 15 against which the shoulder of the cap 13 abuts when the short pencil 11 is projected to operative position beyond the barrel. The barrel is formed at its lower end with a sleeve 16 which slidably receives the cap 10 and forms a guide to direct sliding movement of the short pencil 11 into and out of the barrel.

An angular latch 17 is pivoted intermediate its ends, as shown at 18, on the exterior of the barrel. One end of the latch is bent inwardly to form a finger 19 which is engaged through an opening 20 in the barrel. A helical spring 21 is confined between the free end of the latch and the barrel to normally hold the finger extended into the barrel. When the short pencil is slid into the barrel, the finger 19 passes over the outer annular shoulder 13 of the cap and lodges un-

derneath the shoulder, see Figure 3, to hold the short pencil retracted within the barrel so that its point will not become broken when not in use.

A headed stud 22, see Figure 1, is carried by the barrel adjacent to the shoulder 15 of the barrel and projects through a longitudinal slot 23 in the barrel, see Figure 2. The stud provides means by which the pencil 11 may be conveniently drawn into the barrel.

- 10 A helical spring 24 has its lower end sleeved on the frustum shaped upper end 12 of the cap and seated on the shoulder 13 of the cap. The upper end of the spring is engaged against a shoulder 25 formed on a sleeve 26, which is threadedly engaged with the upper end of the barrel and which receives a cylindrical eraser 27. When the short pencil 11 is withdrawn into the barrel by the operator moving the stud 22, the helical spring 24 will be compressed, see Figure 3.
- 20 When the operator releases the latch 17 by pressure upon its free end, the finger 19 will be withdrawn from underneath the annular shoulder 13 of the cap and permit the spring 24 to expand and move the short pencil 11 to projected position beyond the barrel. The spring then exerts sufficient pressure upon the shoulder 13 of the cap to releasably hold the shoulder against the shoulder 15 of the barrel and prevent relative movement of the pencil and barrel
- 25 while the pencil is in use.

From the above description it is thought that the construction and operation of the invention will be fully understood without further explanation.

35 What is claimed is:

- 1. A pencil, comprising an elongated barrel having a reduced lower end forming an internal shoulder, a cylindrical cap having an open lower end adapted to receive a pencil, an annular flange 40 carried by the upper end of the cap, a frustum shaped extension carried by the cap above the flange, a coil spring carried within the barrel and surrounding the frustum shaped extension and engaging the flange at one end and the upper 45 end of the barrel at the opposite end, a pivoted inwardly spring pressed latch on the barrel with a laterally turned finger passing through the barrel and adapted to pass under the shoulder when the pencil is forced into the barrel, and means 50 carried by the cap and extending out through the barrel for moving the pencil upwardly against the tension of the spring.
- 2. A pencil, comprising an elongated barrel having a reduced lower end forming an internal shoulder and a pencil guide, a cylindrical cap

having an open lower end adapted to receive a pencil, an annular flange carried by the upper end of the cap, a frustum shaped extension carried by the cap above the flange, a coil spring within the barrel and surrounding the frustum shaped extension and engaging the flange at its lower end and the upper end engaging the closed upper end of the barrel, a pivoted inwardly spring pressed latch on the barrel with a laterally turned

5 finger passing through an opening in the barrel and adapted to engage the shoulder when the pencil is forced into the barrel and hold the same against the tension of the spring, and a pin carried by the cap and extending through a slot in the barrel, whereby the pencil may be moved inwardly against the tension of the spring.

JOHN T. HENDRICK.
